HIS ATTORNEY.

UNITED STATES PATENT OFFICE

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY

PNEUMATIC TOOL

Application filed December 3, 1931. Serial No. 578,665.

This invention relates to pneumatic tools, but more particularly to a valve mechanism for tools of this character.

One object of the invention is to retain the distributing valve firmly seated in its limiting positions irrespective of the action of the piston which it controls.

Other objects will be in part obvious and in part pointed out hereinafter.

In the accompanying drawings illustrating the invention and in which similar reference characters refer to similar parts,

Figure 1 is a longitudinal elevation in section of a portion of a rock drill equipped with valve mechanism constructed in accordance with the practice of the invention, and

Figure 2 is a transverse view taken through Figure 1 on the line 2—2 looking in the direction indicated by the arrows.

Referring more particularly to the drawings, A designates, in general, a rock drill comprising a cylinder B having a piston chamber C to accommodate a reciprocating hammer piston D. The piston D is of the differential type having a head F and a stem G at the front end of the head extending slidably through the front end of the cylinder B for delivering blows against a working implement, such as a drill steel (not shown). In the cylinder B is a free exhaust port H which is controlled by the head F of the piston D.

A closure is provided for the rear end of the piston chamber C by a back cylinder washer J having a bore K therein through which extends a rifle bar L to interlockingly engage the piston D in a well known manner for imparting rotary movement thereto. At the rear end of the rifle bar L is a head O which seats upon the back cylinder washer J and carries pawls P for engagement with teeth Q of a ratchet ring R which encircles the head O.

The ratchet ring R and the head O, in the present instance, are arranged within a bore or recess S in the front end of a back head T which is seated on the back cylinder washer J and which may be secured to the cylinder B in any suitable manner.

The distribution of pressure fluid to the

ends of the piston chamber C for actuating the piston D is effected by valve mechanism U arranged, in the present instance, on the side of the cylinder B and comprising a valve chest V which preferably includes a pair of plates W and X bolted, or otherwise secured, to the cylinder B.

The plate W which is seated upon the plate X is suitably recessed to form a valve chamber Y for the accommodation of an oscillatory plate distributing valve Z which is held against longitudinal movement in the valve chamber Y by a pin b seated in the plate W and extending into an aperture c in the valve Z. The oppositely extending wings d and e of the valve are tapered from the transverse median line of the valve towards the outer edges thereof in the usual manner and are adapted to seat upon seating surfaces f and g, respectively, on the plate X.

Leading from the seating surface f to the rear end of the piston chamber C, and extending through the plate X and the cylinder B, is a rear inlet passage h through which pressure fluid flows into the rear end of the piston chamber for driving the piston D forwardly on its working stroke, and said inlet passage is controlled by the wing e of the valve. Similarly, from the seating surface f leads a front inlet passage j which is controlled by the wing d of the valve and extends through the plate X and the cylinder B to the front end of the piston chamber C for admitting pressure fluid thereto to drive the piston D rearwardly.

The pressure fluid controlled by the distributing valve Z may be conveyed to the rock drill by a suitable connection k which opens into a bore o in the plate W. A passage p in the plate W conveys such pressure fluid into the valve chamber Y and is controlled by a throttle valve q.

The rock drill so far described may be of a known type of which the operation is as follows: With the distributing valve Z in the position illustrated in Figure 1, wherein the wing e of the valve is raised and the piston D lies rearwardly of the exhaust port H, pressure fluid flows over the raised end of the wing e through the inlet passage h into the

rear end of the piston chamber C to drive the piston D forwardly on its working stroke. After the piston D covers the exhaust port H the air in the front end of the piston chamber C will be compressed and will act against the seated wing *d* of the valve.

When the compression in the front end of the piston chamber reaches a value together with the force of the suction created by the 10 pressure fluid flowing over the wing *e* exceeds the pressure acting on the upper surface of the seated wing *d*, the valve Z will be rocked to its other limiting position. The supply of pressure fluid to the rear end of 15 the piston chamber will then be cut off and pressure fluid will flow over the raised end of the wing *e* and act against the front end of the valve F of the piston D to drive said piston rearwardly.

20 Normally, in the absence of any force tending to retard the free movement of the piston D, the piston may reciprocate at a rapid rate and the action thereof, together with that of the distributing valve Z, will be substantially 25 as hereinbefore described. In other words, the piston D will travel its full nominal stroke and will deliver a heavy blow against the working implement during each cycle of movement of the piston and of the valve Z.

30 There are instances during the operation of tools of this character when, due to irregularities in the rock being drilled, the working implement becomes stuck or bound in the drill hole to such an extent as to interfere seriously 35 with the rotary movement thereof, such as may be induced by the rotation mechanism including the rifle bar L, its pawls P and the ratchet ring R. Such retardation of the rotation mechanism, in consequence, effects the 40 movement of the piston D.

Whenever the working implement offers great resistance to the action of the rotation mechanism the piston D reciprocates at a reduced rate of speed and, as a result, any pressure fluid which leaks from the valve chamber Y beneath the seated end of the valve and into an end of the piston chamber will therefore build up sufficient pressure in that end of the piston chamber to raise the seated 50 end of the valve. The piston D will then be reversed without completing its stroke. In other words, the valve may be tilted before the piston head F has uncovered the exhaust port H. This is objectionable for the reason that the full force of which the piston D is capable will then not be applied to the working implement to wrest it free from the rock surface.

55 In view of the foregoing facts it is contemplated to provide means intended to assure the retention of the valve Z in its limiting position throughout all periods of operation of the tool until the piston D has completed its nominal stroke, both forwardly and rearwardly. To this end the valve chest, and

preferably the plate X, is provided with a relief valve chamber *r* which communicates with the valve chamber Y through ports *s* and *t*. The port *s* is arranged forwardly of the transverse median line of the relief valve chamber *r* to open into the seating surface *f* or, more particularly, into a recess *u* in said seating surface *f*, and the port *t*, which is located rearwardly of the transverse median line of the relief valve chamber *r*, 70 opens into a recess *v* in the seating surface *g*.

75 Leading from the relief valve chamber *r*, at a point intermediate its ends, is a relief passage *w* which extends through the plate X and the cylinder B and opens to the atmosphere.

80 Disposed in the relief valve chamber *r* is a relief valve *x* which comprises a pair of end heads *y* and *z* connected by a reduced stem 2. The front and rear ends of the 85 valve *x* constitute actuating areas 3 and 4, respectively, against which pressure fluid acts to throw the valve from one limiting position to the other. Such pressure fluid is conveyed to the front end of the valve chamber *r* by a passage 5 which communicates with the inlet passage *j*, and pressure fluid is conveyed into the rear end of the valve chamber *r* from the inlet passage *h* by a passage 6.

85 The manner in which the relief valve *x* operates is as follows: Upon the admission of pressure fluid into the ends of the piston chamber, as for instance, when admitting pressure fluid to the rear end of the piston chamber, a portion of the pressure fluid flowing through the inlet passage *h* passes 90 through the passage 6 into the rear end of the valve chamber *r* and acts against the actuating surface 4 to move the valve *x* forwardly.

95 In this position of the valve *x* the recess *u* will be in communication with the atmosphere through the port *s*, the intermediate portion of the valve *r* and the relief passage *w*. Any pressure fluid then leaking beneath the seated wing *d* of the valve will escape to the atmosphere through these channels and only the compression from the front end of the piston chamber C flowing through 100 the inlet passage *j* will act against a comparatively small area of the seated wing *d*. Such compression, however, will be ineffective to disturb the position of the valve until the piston has reached a position during its 105 forward travel where it will uncover the exhaust port H. When the piston reaches this portion there will be a direct flow of pressure fluid from the valve chamber through the piston chamber and the exhaust port H and the suction of the pressure fluid flowing over the wing *e*, together with the compression acting against the wing *d*, will then tip the valve.

110 In the new position of the valve pressure 115

fluid flows into the front end of the piston chamber C. A portion of such pressure fluid will flow through the passage 5 into the front end of the valve chamber r and act against the actuating surface 3 to move the valve α rearwardly. In this position of the valve α the head y covers the port s and the port t will be uncovered. Thereafter such pressure fluid as may leak from the valve chamber 10 beneath the valve wing e will flow from the recess v through the port t, the intermediate portion of the valve chamber r and the passage w to the atmosphere. Pressure fluid will not, therefore, accumulate beneath the seated wing e. As the piston D moves rearwardly the head F will uncover the exhaust passage H, whereupon the valve Z will again be shifted.

As will be apparent from the foregoing description, only comparatively small areas of the seated ends of the valve will be exposed to such pressure fluid as may leak beneath the valve and, of course, also to compression acting through the inlet passages 25 associated with the several ends of the valve chamber Y. It will further be apparent that the valve α will be shifted in timed relation with the valve Z to maintain a considerable portion of the seated ends of the valve exposed to atmospheric pressure. The valve Z will, in consequence, remain firmly seated in its limiting positions and will not be tilted until the piston D has reached a position to uncover the exhaust port H, irrespective of 30 whether the piston D is reciprocating rapidly or at a slow rate of speed.

I claim:

1. In a pneumatic tool, the combination of a cylinder and a piston therein, a valve chest having a valve chamber, seating surfaces in the valve chamber and having recesses therein, a distributing valve in the valve chamber for distributing pressure fluid to the cylinder, passages for communicating 40 the recesses with the atmosphere, and a second valve movable in timed relation with the first said valve for controlling the passage.

2. In a pneumatic tool, the combination of a cylinder and a piston, a valve chest having a distributing valve chamber and a relief valve chamber, seating surfaces in the distributing valve chamber having recesses therein, ports connecting the recesses with 50 the relief valve chamber, a relief passage leading from the relief valve chamber to the atmosphere, a valve in the relief valve chamber to control communication between the ports and the relief passage, and passages for conveying pressure fluid into the relief valve chamber for actuating the relief valve upon the admission of pressure fluid to the cylinder.

3. In a pneumatic tool, the combination of a cylinder and a piston therein, a valve chest 55 having a distributing valve chamber and a

distributing valve chamber, inlet passages leading from the distributing valve chamber to the cylinder, an oscillatory plate valve in the distributing valve chamber to control the inlet passages, seating surfaces for the valve having recesses therein, ports connecting the recesses with the relief valve chamber, a relief passage leading from the relief valve chamber to the atmosphere, a valve in the relief valve chamber to control communication between the ports and the relief passage, and passages for conveying pressure fluid from the inlet passages into the relief valve chamber to actuate the relief valve.

In testimony whereof I have signed this specification.
